UNITED STATES PATENT OFFICE

WILLIAM BIEDERMAN, OF NEW YORK, N. Y.

APPLICATOR FOR LIQUID COSMETICS

Application filed May 31, 1930. Serial No. 457,802.

This application relates to applicators for liquid cosmetics and the like.

It is an object of this invention to provide apparatus for the application to the skin surfaces or the like of cosmetics or materials having a predetermined medical effect, such as the application of coloring matter to the lips of a person, as is customarily done in the application of lip-stick, or in the use of solution of camphor or similar substances. In conjunction with such apparatus would be used a fluid carrying the desired materials, such fluid utilizing water or some similar liquid as the carrying medium so that there is produced a final solution, emulsion or similar fluid which will react normally in accordance with the ordinary laws of surface tension applicable to liquids which wet a surface.

The apparatus is constructed so that one or more capillary passages are provided through which the fluid may be fed to an applicator tip which is used to spread the fluid over the surface to be coated or moistened. The tip, in suitable cases, may have a slit or similarly sharply defined opening, or may have a pad of felt, sponge rubber, or similar material through which the fluid might be fed for spreading in the desired manner.

By forming an enlargement intermediate of the capillary passage or passages, in any manner, provision may be made for the storage of fluid at any predetermined distance from the point of application, or with relation to a main storage chamber, which may be provided auxiliary to the applicator tip. In a proper case, means may be provided for adjusting the capacity of this storage chamber in accordance with the viscosity of the liquid handled, or to adjust the charge of liquid to be fed to any particular single operation.

It is an additional object of this invention to provide an applicator of the type hereinabove set forth and in which a primary reservoir is located adjacent the end of the applicator, wherein a device is assembled within the reservoir and is operable to limit the flow from the end of the applicator

when the force of gravity is added to the capillary force acting to move liquid through the passages. Such device may also operate to trap liquid within the reservoir when the passage is positioned upright and the tendency of gravity would be to draw the liquid downwardly through said passages and away from the applicator tip.

It is a further object of this invention to provide an applicator nozzle having two or more capillary passages leading therethrough substantially in parallel relation, the capillarity of at least one passage being less than that of the other so that, as the applicator tip is applied to the surface to be moistened, the passage capable of exerting only the lesser capillary force will become an air vent for the reservoir with which it is assembled. The reduction in capillary effect in any one passage may be accomplished in any suitable manner, as by variation of the diameters of the passages. A preferred method, however, is to increase the capillary action in one passage by inserting a very fine wire thereinto.

It is an object of the invention to provide an applicator of the type herein described which will be capable of feeding fluid for coating or moistening a surface which is disposed in any plane relative to the applicator, that is, a surface above, as well as a surface below the applicator, and one vertically disposed, as well as one horizontally disposed. For this purpose, the property of certain fluids, known as surface tension, is utilized to effect the feeding of such fluid upwardly, or in any other direction, for attaining the desired coating or moistening of said surface.

The applicator discharge end may, for the purposes of this invention, be disposed in a vertical, as well as a horizontal, or like plane. In any case, suitable vents are provided to assure the necessary flow of liquid to the final discharge orifice or like feeding means. No particular method of venting the storage chamber or like supply source of liquid is intended to form a specific part of the generic invention herein involved; however, certain specified methods of vent-

ing have been designed which cooperate with the generic invention to effect combinations claimed by me as specific inventions. The invention may be incorporated into a suitable device capable of being carried in a purse or may, in any other suitable manner, be assembled for use.

Other objects of this invention will be apparent from the drawing and from the 10 description thereof, or will be specifically indicated therein.

The invention is not intended to be restricted to the construction and arrangement of parts herein shown and described, nor to 15 the various details thereof, as the same may be modified in various particulars without departing from the spirit and scope of the invention, some practical embodiments of which have been herein illustrated and described without attempting to show all the 20 various forms and modifications in which the invention might be embodied.

On the drawing, wherein are disclosed 25 several preferred embodiments of the invention,

Fig. 1 is a vertical diametrical sectional view of an assembled applicator, embodying the invention.

Fig. 2 is an elevational view of a portion 30 of said applicator, with the top cap removed, and the nozzle turned through ninety degrees and broken away to illustrate the relation of the passages therein.

Fig. 3 is a vertical sectional view through 35 a modified embodiment of the invention, illustrating a method of adjusting the capacity of the reservoir of the applicator.

Fig. 4 is a side elevational view of a detail 40 of a modified form of the invention, shown broken away in part to illustrate the internal construction thereof.

Fig. 5 is a front elevational view of the applicator shown in Fig. 4.

Fig. 6 is an elevational view of a further 45 modification of the invention, broken away to illustrate the construction of the applicator tip portion thereof.

Fig. 7 is an elevational view. 50 Fig. 8 is a plan view of a further modified form of the invention.

Fig. 9 is a vertical sectional view through a further modified form of the invention.

In the particular construction of Figs. 1 55 and 2, the invention is seen to have been embodied into a container 10, which may be made of any suitable material for retaining liquids therein, and which may lend itself readily to formation into such ornamental 60 shapes and the like for commercial purposes as may be desired. Preferably, the container is of small diameter or cross-section, and consists of a tube 12, to which may be secured, in any desired or well-known manner, a bottom 14, such bottom being made

readily removable for refilling or similar purposes.

The other end of tube 12 may have assembled therewith a nozzle cap 16, removably retained upon the tube, as by means of 70 screw threading or the like. Through the cap is formed a bore 18, within which the body 20 of the applicator 22 is received and retained.

The applicator, in a preferred, but not a 75 necessary, form, is made up of a pair of mated sections 24 and 26. The applicator could be made in any other suitable manner, as by drilling, or otherwise working, a solid piece of metal or the like. The 80 mated sections may be formed out of bakelite, hard rubber or similar substances which the liquid to be used therewith will wet, the mating surfaces of the sections being substantially flat throughout. In portion 28 of 85 the applicator, the surfaces are intended to conform accurately to each other so as to provide a liquid-tight fit when the sections are united, the surfaces having no spacing therebetween except at cut-out portions in 90 each of the sections which are mated to produce a duct 30.

At the external portion 32 of the applicator, adjacent the nozzle cap, the flat surfaces of the opposed sections are separated 95 an appreciable extent to provide a passage 38, the surfaces then either continuing at the same degree of separation, or converging to a fine line opening 40 at the exterior surface of the applicator. The junction 100 edges of the sections contiguous to passage 38 are sealed together in any well-known manner to provide a water-tight, non-leaking connection. At the point of origination of the passage, the duct 30 is completely 105 or substantially lost therewith. The two surfaces of the mated sections at passage 38 are separated to such degree that but a capillary passage is produced therebetween, so that liquid deposited at the beginning of 110 the passage will be fed, due to the effect of surface tension, to the outer end or tip of the applicator.

The principal result of the invention herein does not, however, require the specific 115 construction hereinabove set forth, as arrangement of one or more capillary passages of any particular constructions may be utilized for the purpose herein set forth. Liquid fed to the outer end or tip of the 120 applicator by any means, that is, either by capillary force in the passage or by the gravitational or like force exerted by the body of the liquid within the chamber of container 10, will moisten the tip so that, 125 when the tip end is moved across any surface to be moistened, such as the lips of a person, when the applicator is used for spreading liquid lip-stick, the moist end will wet the surface, so that, as the applicator 130

end moves onward, the joinder of the liquid film and the liquid in the applicator will cause a movement of liquid through the duct or capillary passages of the applicator, the liquid therein moving to compensate for that liquid which has been removed, due to the effect of the forces of surface tension.

To clarify still further, the union of the body of liquid within the applicator passages or ducts with the wetted surface results in the application of a force upon the body of liquid adjacent the tip opening, drawing it out therefrom as the liquid in the applicator end seeks to join the liquid wetting the surface, due to the fact that a liquid tends to assume the smallest possible surface under the circumstances. This force externally of the applicator will be greater than the similar force applied to the liquid within the tubes or passages by the walls thereof, because of the greater extent of the external surface, and the liquid within the passages will tend to move toward the liquid deposited externally. In other words, as the applicator continues to move over the surface to be coated or wetted, the flow of liquid from the passages will continue so long as there is a liquid connection between the external liquid and the liquid within the tube, or so long as the latter holds out.

Where the tube is held vertically, so that liquid would flow down into the capillary passages under the force of gravity, the supply going to the surface to be moistened will be limited only by the contents of the container. However, where the tube is held vertically upward and the force of gravity is not operative to lift the body of liquid from the container into the capillary passages of the applicator, the extent of application possible is limited by the quantity of liquid having direct liquid connection with the liquid at the tip end of the applicator, as can be readily understood.

In order to facilitate the capillary feeding of liquid between the two complementary flat surfaces, hair line depressions 42 are provided to constitute a plurality of capillary passages when the sections 24 and 26 are mated. In this manner, the necessity for having the convergence of, or the close approach of the surfaces to each other with any considerable accurateness is avoided.

In order to provide a quantity of liquid for use at the applicator tip, in whatever position it may be used, it is found desirable to have a secondary storage chamber of small capacity adjacent the outlet from the applicator. For this purpose, a suitable enlargement 44 of the duct 30 is formed within the body of the applicator in close adjacency to the tip end and substantially at the commencement of the final capillary passages. In this manner, liquid may be

fed to the enlargement through the duct 30 and be retained therein. A thin film of liquid will form in the passage 38 and, in most cases, will be liquidly connected with the liquid in the enlargement; the inability of atmospheric pressure to break down this film of liquid will act as a seal, under normal circumstances, to retain the liquid, so fed, trapped in the enlargement. Then, when it is desired to make use of the liquid thus stored, the applicator tip is applied in the customary manner, and liquid will flow from the enlargement into the capillary passages and then out thereof in the manner hereinabove set forth.

It may be desired to protect the applicator against excessive discharge when apparatus of the type hereinabove set forth is used with the applicator tip pointed substantially downward and gravitational force is exerted by the body of liquid within the chamber of the container upon the liquid in the passages. For this purpose, a ball 46, preferably of metal, may be housed within the enlargement 44 and is adapted to coat with a seat 48, formed at the opening of the capillary passages into the enlargement, to cut off flow from the enlargement to such passages when the applicator tip is positioned with the tip portions thereof pointed downwardly.

Likewise, to safeguard against the loss of liquid from the enlargement when the tip is pointed vertically upward, and against the possibility of breaking the liquid seal at the tip, in which case the liquid in the enlargement may flow down the duct and into the reservoir of the container 10, an additional seat 50 may be provided at the junction of the duct 30 with the enlargement. When the applicator is positioned with the tip portion thereof pointed vertically or substantially so upwardly, the ball 46 will coat with the seat 50 to close off communication between the enlargement and the duct.

Some suitable means must be provided for venting the chamber of the container 10. For this purpose, the nozzle cap 16 is provided with one or more air vent passages 52 which extend therethrough and provide open communication between the exterior of the container and the interior thereof. Preferably, these passages taper inwardly so that the liquid within the container, when the container is positioned with the applicator tip downwardly, will be restrained against flowing down through the air vents, while air will be permitted free access to the container at any other time. As appears at 54, I have found the end of a hypodermic needle, with the tip thereof positioned within the chamber and the other end thereof externally of the container 10 to serve efficiently the purposes intended.

In order that the container and the attached applicator tip may be carried in such means as a pocketbook or the like, a cap 56 is provided, and may have means for screw-threadedly engaging the outer surface of the nozzle cap to close the cap down against the nozzle cap and also to bring a rubber or like cushion 58 retained within the end of the cap down upon the end of the applicator tip, thus to seal the latter. The cushion will also serve to maintain a film of liquid at the tip, after once moistened, so that the tip will be prepared for instant use, upon the removal of the cap. Preferably, the shoulder 60 of the nozzle cap and the face 62 of the cap are formed to cooperate in such manner that, when the cap has been brought down against the nozzle cap, the shoulder 60 will tightly abut the face 62 and substantially seal off the ends of the air vent passages.

In Fig. 3 is shown a modified form of the applicator tip which is adapted for use either in connection with a primary reservoir such as provided by a container 10, or in any other similar relation. The applicator 64 in this modification may be made of material similar to that used for applicator 22; also, the applicator may be made up in substantially the same manner, that is, by the use of two sections, brought into abutting and mating relation, although in either case, it is not essential that such construction be followed to attain the desired form. In the case of applicator 64, a duct 66 is formed by the mated sections, the passage leading to a reservoir chamber 68, from which a capillary passage 70, or a plurality thereof, formed in substantially the same manner as the passages set forth for applicator 22, lead away to the tip end 72. Within duct 66 is positioned a plug 74, substantially tightly fitted in the duct, but which may be moved in said duct so that the capacity of the chamber 68 may be effectively varied by changing the position of the plug with relation thereto.

Due to the tightness of the plug in the chamber, the ordinary shocks of carrying such an article will not jar the plug out of a set-up position. In order to permit the feeding of liquid from the chamber of the container with which such applicator is assembled, one or more capillary or like ducts 76 are provided in the walls of the duct 66 or in the face of the plug, and extend substantially the entire length thereof. In this manner, the plug is by-passed and liquid supply for the reservoir chamber set up.

A ball 78 may be retained by the plug within the reservoir chamber to coact with a suitable seat 80 at the entrance to the capillary passages 70, as set forth above for the ball 46. The capillarity of ducts 76 will substantially prevent any back-flow

therethrough, so that no other means is necessary to check such flow.

For venting apparatus of the character set forth above, and as shown in Fig. 3, it is possible to use passages similar to the air vent passages 52 in the nozzle cap or to provide a vent passage 82 which may be formed lengthwise through the applicator body, opening at the external face 84 of the applicator and into the chamber of the container with which the applicator is assembled. The passage 82 may be shaped in a manner similar to the passages 52, that is, converging inwardly, to prevent, to a substantial degree, the outflow of liquid therethrough at undesirable times. By this means, liquid will be permitted movement up through the capillary passages 70 to the tip end while air will move down the vent passage to the chamber of the container to compensate for the reduction of pressure therein as liquid is withdrawn.

In Figs. 4 and 5, a further modification of the invention is disclosed in which the capillary passages, instead of opening at the extreme tip of the applicator, open along a surface 86 at the side of the applicator. It is to be understood, in this connection, that the particular location of the applicator tip or surface is of no specific import since, as in this illustration, it may open at the side of the applicator, as well as at the extreme end. In this construction, the applicator end is not formed with the line opening, as are the modifications previously discussed; a substantial opening is provided within which is seated a pad 88 of felt, sponge rubber or similar material which, in itself, exhibits capillary functions. Liquid brought into contact with the pad will thus wet the same and be conducted to the outer surface thereof to be applied to any surface with which the pad is brought in contact.

A reservoir 90 may be provided in connection with an applicator of the type herein set forth, and an air vent 92 open through the walls of the applicator from said reservoir to the atmosphere. Preferably, such vent would be tapered inwardly, in the same manner, and for like purposes, as previously set forth.

A further modification of the invention is disclosed in Fig. 6, in which case the flat surfaces 94 forming the capillary passages are dented, as at 96, in any suitable manner, to provide small pockets or recesses for receiving and retaining small supplies of liquid, as the same is fed through the passages. Thus, as liquid passes through the capillary passage, these pockets will provide small reservoirs for holding reserve supplies of liquid; should the effect of capillarity be lost at a lower point, these supplies will become effective and will be fed to the outer

end of the applicator to augment the charge otherwise available.

In Figs. 7 and 8, a method of conducting air to the container and of providing for the capillary action of the necessary passages is shown. In this case, the surfaces of the mated members 98 and 100 are not complementary but are substantially convexed so that but a small portion of one is contacted with a small portion of the other. The other portions of the surfaces are free of each and substantially diverge away from each other. Thus, at some point, the effect of the force of surface tension will be broken between the two surfaces and a free area will be presented, along which air may be conducted to the interior of the container. For this purpose and in this connection, it is also feasible to coat a portion of the complementary surfaces with some means, such as an oily substance, which will reduce the coefficient of adhesion for the liquid to the surface to substantially zero; liquid then will not wet the surface and will draw away from that portion of the surface under the effects of surface tension. Such portion of the surface can therefore be utilized for the purpose of conducting air to the interior of the container.

In Fig. 9, there is disclosed a modification of the invention in which the applicator 102 has formed therein a pair of capillary passages 104 and 106, leading up to the common tip 108. The tip end, for the purposes of the invention, is not made straight across the end but preferably is slightly curved so that, in use, the entire face will not contact the surface to be wetted. For the purposes of the invention, one of the passages is preferably made capable of exerting a lesser capillary force than the other, either by making the diameter thereof greater than that of the other, or, as in the arrangement herein shown, by inserting a fine wire 110 in one of two passages of equal diameter. Thereby, the effect of liquid upon the surface of the wire is added to the effect of liquid upon the surface of the passage and the force in such passage is thereby increased over that of the other passage. When application takes place, liquid will normally travel down the passage having the wire 110 therein, while air will flow up the other passage or passages of lesser capillary force.

As many changes could be made in the above constructions and many apparently widely different embodiments of the invention designed without departing from the scope and spirit of the invention, as defined in the accompanying claims, it is intended that all matter contained in the above description or shown in the drawing shall be interpreted as illustrative merely of an op-

erative embodiment of the invention and not in a limiting sense.

It will be understood that depressions or recesses such as shown at 94 and 96 may be located, if desired, within the one or more of the capillary passages.

It will also be understood, of course, that where a plurality of capillary passages or tubes are provided, as for example in Fig. 9, these passages may vary in cross sectional area and one or more of such capillary passages may be sub-divided longitudinally so as to provide a multiplicity of smaller capillary grooves or channels within one or more of the major passages. Where a plurality of capillary passages are provided, these, of course, may vary in length.

I claim:

1. A liquid lip-stick applicator, including an applicator nozzle, a liquid-trapping storage chamber intermediately of the applicator nozzle, and a capillary passage in the applicator nozzle communicating with said chamber and being operative to bring liquid from said chamber to the exposed end of said applicator against the action of gravitational force.

2. A liquid lip-stick applicator, including an applicator nozzle, a liquid-trapping storage chamber intermediately of the applicator nozzle, and a plurality of capillary passages in the applicator nozzle communicating with said chamber and being operative to bring liquid from said chamber to the exposed end of said applicator against the action of gravitational force.

3. A liquid lip-stick applicator, including a liquid storage chamber, and an applicator having a capillary passage communicating with said chamber and when in use leading upwardly away from said chamber to the exposed end of said applicator, the cross-section of said passage decreasing from the chamber end to the exposed end thereof to make the passage operative to bring liquid from the chamber to the exposed end of the applicator against the action of gravitational force.

4. In combination, a liquid storage chamber, and an applicator having a passage communicating with said chamber, said passage being formed between two substantially complementary surfaces positioned closely adjacent each other and leading from said chamber to the exposed end of said applicator to bring liquid from said chamber to the exposed end of the said applicator against the action of gravitational force.

5. An applicator nozzle for attachment to a liquid lip-stick container, the nozzle having a capillary passage therein for communication with the interior of said container, said passage leading to and opening at the applicator end of said nozzle, the nozzle and container being constructed to feed the liq-

- uid against gravitational effort when the applicator end is in use.
6. An applicator nozzle for attachment to a liquid lip-stick container, the nozzle having a capillary passage therein for communication with the interior of said container, said passage leading to and opening at the applicator end of said nozzle, and being enlarged intermediately of said nozzle to form 10 a liquid reservoir in proximity to said applicator end, the nozzle and container being constructed to feed liquid against gravitational effort when the applicator end is in use.
- 15 7. An applicator nozzle having a capillary passage therein leading to and opening at the applicator end of said nozzle, said passage being enlarged intermediately of said nozzle to form a liquid reservoir in proximity to said applicator end, and a member in 20 said reservoir adjusting its position in accordance with the position of the nozzle, said member operating to close said passage against the flow of liquid therethrough.
- 25 8. An applicator nozzle having a capillary passage therein leading to and opening at the applicator end of said nozzle, said passage being enlarged intermediately of said nozzle to form a liquid reservoir in 30 proximity to said applicator end, and a member in said reservoir automatically adjusting its relation to the passage to close said passage against the return flow of liquid away from the applicator end.
- 35 9. An applicator nozzle for attachment to a liquid container having a capillary passage therein for communication with the interior of said container, said passage leading to and opening at the applicator end of said 40 nozzle, and being enlarged intermediately of said nozzle to form a liquid reservoir in proximity to said applicator end, the applicator end consisting substantially of a surface of inconsiderable width, and a member in said reservoir to close said passage against the flow of liquid from said reservoir to said container or from said container directly into said capillary passage and operating to trap liquid within the reservoir as the nozzle is tilted into various positions.
- 45 10. In combination with a liquid lip-stick container having an opening therein, an applicator nozzle assembled at said opening and having a capillary passage therein for communication with the interior of said container, said passage leading to and opening at the applicator end of said nozzle, the nozzle and container being constructed to 50 feed liquid against gravitational effort when the applicator end is in use.
- 55 11. An applicator nozzle having a capillary passage therein leading to and opening at the applicator end of said nozzle, said 60 passage being enlarged intermediately of said nozzle to form a liquid reservoir in proximity to said applicator end, and a member freely movable in said reservoir to close said passage against the flow of liquid therethrough.
- 65 12. In an applicator, a nozzle having an applicator surface at an end thereof, a capillary passage leading through said nozzle to said surface, said passage being enlarged intermediately of said nozzle to form a chamber therewithin, and adjustable means in 70 said chamber for varying the effective capacity thereof.
- 75 13. In an applicator, a nozzle having an applicator surface at an end thereof, a capillary passage leading through said nozzle to said surface, said passage being enlarged intermediately of said nozzle to form a chamber therewithin, means in said chamber for reducing the effective capacity thereof, and a member in said chamber to check the flow therefrom when said applicator surface is positioned downwardly.
- 80 14. In an applicator, a nozzle having an applicator surface at an end thereof, a capillary passage leading through said nozzle to said surface, said passage being enlarged intermediately of said nozzle to form a chamber therewithin, adjustable means in 85 said chamber for varying the effective capacity thereof, and a member in said chamber to check the flow therefrom when said applicator surface is positioned downwardly.
- 90 15. In an applicator, a nozzle having an applicator surface at an end thereof, a capillary passage leading through said nozzle to said surface, said passage being enlarged intermediately of said nozzle to form a chamber therewithin, a plug tightly fitting 95 in said chamber and movable therein for varying the effective capacity thereof, and capillary passages by-passing said plug.
- 100 16. In an applicator nozzle having an applicator surface at an end thereof, a capillary passage leading through said nozzle to said surface, said passage being enlarged intermediately of said nozzle to form a chamber therewithin, a plug tightly fitting 105 in said chamber and movable therein for varying the effective capacity thereof, capillary passages by-passing said plug, and a member in said chamber to check the flow therefrom when said applicator surface is positioned downwardly.
- 110 17. In an application, a nozzle formed of two substantially complementary surfaces positioned closely adjacent each other and operative to transmit liquid therewith to the exposed end of said applicator, said surfaces being formed with a plurality of indentations, as and for the purposes described.
- 115 18. In an applicator, a nozzle formed of two substantially complementary surfaces positioned closely adjacent each other and operative to transmit liquid therewith to 120
- 125
- 130

the exposed end of said applicator, portions of said surface being cut away to provide air venting means.

19. An applicator nozzle consisting of a body portion formed with a tip having an applicator surface at an end thereof, and a pair of capillary passages leading to and opening at said surface, said surface being slightly curved, as and for the purposes set forth.

20. An applicator nozzle consisting of a body portion formed with a tip having an applicator surface at an end thereof, and a pair of capillary passages leading to and opening at said surface, one of said passages being of a lesser effective cross-section.

21. An applicator nozzle consisting of a body portion formed with a tip having an applicator surface at an end thereof, and a pair of capillary passages leading to and opening at said surface, one of said passages, when filled with liquid, being affected by a greater capillary force than the companion passage.

22. An applicator nozzle consisting of a body portion formed with a tip having an applicator surface at an end thereof, a pair of capillary passages leading to and opening at said surface, and a wire in one of said passages.

23. In combination, a liquid storage chamber, and an applicator having a plurality of passages communicating with said chamber, said passages being formed between two substantially complementary surfaces positioned closely adjacent each other and leading from said chamber to the exposed end of said applicator, the cross-section of said passages decreasing from the chamber end to the exposed end thereof.

24. In an applicator, a nozzle formed of two substantially complementary flat surfaces positioned closely adjacent each other and operative to transmit liquid therealong to the exposed end of said applicator, said surfaces being formed with a plurality of indentations, as and for the purposes described.

In testimony whereof he has affixed his signature.

WILLIAM BIEDERMAN.
